UNITED STATES PATENT OFFICE

RAYMOND W. DULL, OF CHICAGO, ILLINOIS, ASSIGNOR TO LINK-BELT COMPANY, OF CHICAGO, ILLINOIS, A CORPORATION OF ILLINOIS

APPARATUS FOR MAKING CHAIN

Application filed June 7, 1924. Serial No. 718,427.

My invention relates to an apparatus for making chain from a strip of sheet metal stock, and particularly to a machine for the continuous making and automatic assembling of the links into a chain. The general object of my invention is to produce chain of the type described in which hook and pintle tongues are stamped from the center of the link blank and the hook and pintle end bars are bent to produce a chain, each link of which consists of flat side bars, a relatively cylindrical hook at one end, and a pintle at the other shaped for rotation within the hook of the link next adjacent. One object is to provide a mechanism for producing chain of the type described, with maximum cheapness and simplicity. Another object is to provide a mechanism which shall stamp the hook and pintle tongues from the center 20 of the blank and curl them and the end bars into finished hooks and pintles with a minimum strain upon the metal of the blank, and a minimum weakening and distortion of the fibers of the metal. Another object is to provide a mechanism for producing chain of the type described in which, by scoring and by indenting each blank, the tendency of the end bars to tear out shall be reduced to a minimum. Another object is to provide a mechanism for producing chain of the described 30 type in which the length of the blank as it passes through the device shall vary as little as possible during, and be reduced as little as possible, by the successive die impacts.

Other objects will appear from time to time in the course of the specification and claims.

I illustrate my invention more or less diagrammatically in the accompanying drawings, wherein—

Figure 1 is a plan view of the strip of material operated upon, illustrating the effect of the successive die impacts;

Figure 2 is a section along the line 2—2 of Figure 1;

Figure 3 is a plan view similar to Figure 1, but showing the under side of the stock;

Figure 4 is a skeleton side elevation of the punch and die, illustrating the passage of the stock therethrough, and its formation into links;

Figure 5 is an inverted plan view of the punch;

Figure 6 is a top plan view of the die;

Figure 7 is a section on the line 7—7 of Figure 4; and

Figure 8 is a section on the line 8—8 of Figure 4.

Like parts are illustrated by like characters throughout the specification and drawings.

A is any suitable base having mounted thereupon the die block A¹, which may be secured thereto, for example, by the wedge A², downwardly drawn by the bolts A³, and engaging with its inclined overhanging wall A⁴ the opposite inclined wall A⁵ of the block. The opposite side of the block is gripped by the overhanging inclined wall A⁶ of the base.

B is any suitable strip of relatively resistant material upon which rest the individual die elements. These elements are gripped and aligned in any suitable manner, for example by the opposed holding blocks B¹, B², which may be connected together, for example by the bolts B³. The individual die 75 elements will later be discussed in detail.

The chain is formed by the passage, between opposed die and punch elements, of the strip of stock C, which is moved forwardly therebetween by a step-by-step movement, so by any suitable feeding means, the details of which need not be shown herein. At each successive forward movement the punch element is moved downwardly against the die element by any suitable press mechanism. The punch and die are aligned, for example, by the vertical guiding columns, J, J, in rigid relation with the die block A¹, and upon which the punch block K is slidably mounted.

The punch block K is clamped into any suitable working backing K¹, for example by the set screws K² in the punch block. The opposite side K⁵ of the punch block is engaged by the opposed overhanging surface K⁶ of the backing element K¹. K⁷ is a base element similar to the base element B of the die block. K⁸ and K⁹ are lateral clamping elements secured together about the individual punch elements in any suitable manner.

The passage of the metal strip C over the die block is from right to left, as shown in Figure 4. This ribbon or strip of stock C may be initially straightened and fed by any suitable means not herein shown, and is guided into the machine, for example, by the pair of opposed rollers C¹, C¹, which are centrally grooved as at C² and are rotatable upon and axially slid able in relation to the vertical pins C³, C³. Movement of the rollers upon the pins is limited by the washers C⁵ and nuts C⁶. The rollers are preferably, but not necessarily, laterally adjustable. The blocks B¹, B² are slotted near their ends to permit the adjustment of the pins C³, C³ which are clamped in position by the nuts C⁴, C⁴.

Depending from the punch block and positioned adjacent the point of severing of the partly completed link from the strip stock, as later described, are depending strip-engaging elements comprising the opposed, inwardly slotted, edge-gripping yokes D, D, the edges of the strip C being positioned between the inwardly projecting pairs of flanges D¹, D¹. The set screws D², D² provide means for centering the strip C within the guiding yokes. The yokes are suspended upon, or are at the lower ends of, the cylindrical plungers D⁴, which are spring pressed by the spiral springs D⁵, which are kept in position by the guiding cores D⁶ screw-threaded into the top of the punch block element K¹. The downward movement of the plungers D⁴ is limited, for example by the stops D⁸, which abut against the shoulders D⁹ of the plungers. The die block is cut away in shape, as at D¹⁰, D¹⁰ to receive the elements D when the travel of the punch brings the strip C in contact with the die.

It will be understood that the strip C is guided by, and in a sense suspended between, the opposed rollers C¹ and the opposed guiding yokes D, and intermediate the forming impacts is suspended between die and punch in the position shown in Figure 4. The straight sides of the link stock are not bent until after the stock has passed through the guides D¹.

Since the separate punch and die elements operate in pairs upon the strip of metal passing step by step therebetween, they will be described in pairs, and in relation to the impression they make upon the stock. As the stock C is passed forwardly between the rollers C¹ it is first operated upon by a pair of prick punches L, L, upon the die, which prick punch the corners of the future link at the inside corners where the side bars and the pintle end bar join. The top of the blank at this point is merely held against upward movement by the opposed plane surface L¹. In describing the effect of the various die elements, the element and the impression made thereby will in general be given the same in-

dicating symbol. At the next forward step of the stock it is engaged both top and bottom by the opposed, H-shaped scoring knives L³ on the die and L⁴ on the punch. These knives score the metal along the separation between the future hook and pintle tongues and side bars and between the opposed inner edges of the hook and pintle tongue. The scores extend from the punch marks l, as shown in Figure 3. Since the hook tongue is necessarily much longer than the pintle tongue, the cross scores l⁵ are near the pintle end of the future link. At the next forward movement of the stock, the top of the stock is engaged along the transverse score l⁶ by the transverse severing knife L⁷. The knife shears the metal along the transverse score l⁶ and bends or curves the hook tongue around the curved die surface L⁸, and bends the pintle tongue around the creasing bead L⁹ on the die, thus creasing or scoring the inside of the bend of the pintle tongue between the punch marks l, l. The end of the future hook tongue is by this operation given its preliminary curvature or formation, which preferably conforms substantially to the arc of the future hook tongue. At the next forward step of the stock the separation between the hook and pintle tongues is enlarged by the forming element L¹⁰, which further bends the end of the hook and pintle tongues, the end of the hook tongue being rolled about the rounded corner l¹¹ of the yieldingly mounted block E, the block being normally held in raised position by the spiral spring or springs E¹ and serving to lift the strip C from the block as the punch is withdrawn. At the same time, the bottom of the stock is prick punched by the punches L¹² upon the yieldingly mounted block E, which are positioned to indent the bottom of the stock at the opposite end of the longitudinal scores from the punch marks l. At the next forward movement of the stock the severing of the hook tongue from the side bars is finally completed by the inclined punch element L¹⁴, the forward inclined portion of which shears the hook tongue from the side bars while the opposite end of it further bends the pintle tongue about the sharp corner L¹⁵ of the yieldingly mounted block E. Meanwhile the transverse scoring knife L¹⁶ deeply scores the top of the stock, outlining the separation between the adjacent future links. The punch element L¹⁴ has projecting slightly from both sides the parts L¹⁷, L¹⁷, which cut the notches l¹⁸, l¹⁸ near the pintle end of the link which prevents binding of the hook end in the finished chain.

Up to this point the edges of the strip stock C have not been bent and the entire operation of the opposed punch and die elements has been upon the central portion of the future link. At the next forward movement of the stock, however, the punch element M, which has substantially the cross-section of the cen-

tral aperture of the link, punches out or moves the hook tongue to the position shown at M^1 in Figure 2. Along the base of the punch M are the inclined punch ledges M^2 , adapted to engage the side bars of the link and bend the link into the position shown at m^3 in Figure 2. Rounded ends M^4 , M^5 of the base of the punch block M operate against the corresponding die elements M^{10} , M^{20} , and bend the hook and pintle bars, respectively, of the link to the form shown as m^6 , m^7 in Figure 2.

Associated with the punch elements L^{10} and M are the spring pressed plungers P normally downwardly compressed by the spiral springs P^1 . The lower ends of the plungers engage and exert pressure against the side bars of the link or stock and assist in freeing the stock from the punch and preventing adherence of the stock thereto.

At the next movement of the stock the cutting edge N , formed by a downward offsetting of that end of the punch in relation to the rest of the punch, shears along the transverse score N^6 and against the opposed cutting edge N^1 of the die and severs the partly completed link from the stock. As the stock is forced down by the punch prior to this severing, the side bars of the link are engaged by the longitudinal lugs G^1 of the yieldingly mounted block G and are locked thereby against the punch element N^2 , which is provided with a central portion N^3 , penetrating within the central aperture of the link, and side bar engaging surfaces N^4 in opposition to the tops of the lugs G^1 . The pressure of the heavy spiral spring G^3 is sufficient to straighten out the link prior to the severing, as shown in Figure 4, and the link when severed is firmly gripped between the block G and the punch element N^2 and is carried downwardly by the downward travel of the punch.

The curved portions N^5 , N^6 of the punch N^2 engage, respectively, the bent hook and pintle end bars as the link is carried downwardly by the punch, the end of the hook tongue engages the rolling die surface N^{10} and is thereby curved into the position n^7 , as shown in Figure 4. Prior to the completion of this rolling movement the pintle tongue contacts the die surface N^8 and is bent into the position shown in Figure 4. The rolling movement of the hook tongue is limited by the stop N^{10} adjacent the surface N^5 of the punch element N^2 .

Meanwhile the previously completed links of the chain are passing forwardly between channel iron guides H , which are connected, for example, by the cross-pieces H^1 , the ends of which are perforated to slide upon the pairs of vertical guides H^2 and are kept normally in raised position, as shown in Figure 4, for example by the spiral springs H^3 . The cross-pieces may be engaged, for example by any suitable element or elements H^4 on the

punch element, out of alignment with the fixed pins H^2 and preferably engaging the cross-pieces H^1 . The heads H^5 of said pins serve as stops to limit the upward movement of the cross-pieces H^1 and the guides H in response to the springs H^3 .

It will be realized that while I have shown an operative mechanism many changes might be made in the size, shape, number and disposition of parts, and that I wish my description and drawings to be taken as in a broad sense illustrative and diagrammatic, rather than as limiting me to the specific mechanism herein shown.

The use and operation of my invention are as follows:

I manufacture chain from a ribbon or strip of sheet metal stock which is fed forwardly, step by step, between opposed punches and dies. The interval between the forward feeding movement need be only sufficient to permit the strip to move forwardly through the press the length of one link.

In order to prevent interference between the stock and the punch or die at the time of such forward movement, I provide means for lifting the entire strip of stock from the die and for suspending it between die and punch intermediate the forming impacts, and for giving it its forward movement when so suspended and out of contact with either punch or die.

In the form herein shown, I move the strip upwardly, after each impact, to a position substantially midway between punch and die, when the punch is withdrawn to its maximum height. I accomplish this lifting movement in two main steps: The yieldingly mounted block E is upwardly raised by the spiral spring or springs E^1 as soon as the punch is withdrawn from contact with the strip, and the compression of the spring E^1 is sufficient to lift the block, and with it the strip, sufficiently to break the strip C from the dies and to prevent any tendency it might otherwise have to adhere thereto. Any tendency of the strip to cling to the punch elements is obviated by the plungers P and the spiral springs P^1 , which are shown at two points upon the punch block, which, of course, might be increased in number, if necessary under any particular working conditions. These elements, pushing upon the side bars of the link, clear the stock from the punch. As the punch is lifted, the guides D remain in contact with the opposed die surface D^{10} until the stops D^8 engage the ledges D^9 on the plungers, this occurring in practice about midway in the upper excursion of the punch. By this time the strip has already

been freed from both punch and die elements and is lifted upwardly with the punch and suspended intermediate the punch and die, as shown in Figures 4 and 7.

The strip is fed into the space between

punch and die through the rollers C¹, which may be made transversely adjustable in relation to each other. However, they automatically compensate, within a certain range, for 5 variations in the thickness of the stock, and the stock is centered by the opposed converging lower surfaces of the rollers. The stock cannot be jammed or caught in the rollers, since the rollers rotate in response to the forward 10 movement of the stock and tend always to clear it. The rollers are vertically movable and will compensate to such slight upward movement of the stock as may take place at that point in response to the upward 15 movement of the guides D.

In the form of punch and die herein shown, the portions of the link which are forced out of the normal plane of the strip are all bent downwardly toward the die, and it is therefore necessary to lift the strip above the die 20 to a distance greater than the length of the hook tongue.

In the method of forming the chain herein described, the side bars of the links are 25 not deformed or bent until shortly before each link is severed from the chain stock. Therefore the stock, throughout most of its excursion between punch and die, is straight-edged, and can easily and efficiently be formed 30 wardly fed through the guides D.

The strip metal stock, of which the links are formed, is a fibrous material and is, of course, tough and hard. In making links from it, it is necessary not only to render 35 easy the severing of the parts which have to be severed and to make this severing possible without a damaging distortion of the material, but also to limit the severing and to counteract the tendency for further and unintended tearing or severing, either during 40 manufacture or during later use of the chain. To make the severing easy, the parts to be severed are initially scored. To prevent further unintended tearing, the lines of score are 45 terminated by indentations which break up the normal fibrous structure of the material and prevent the formation of continued lines of weakness and cleavage beyond the lines of score and separation.

50 The weakening of the link is further avoided by performing the major severing operations not by one impact but by a succession of impacts. The distortion of the metal at any one point is reduced to a minimum, and 55 at the sharp bends or corners where the material of the stock is compressed by bending the blank is provided with creases and with indentations which serve to give space for the material compressed, for example along the 60 inside of the pintle tongue, and at the inside corners of the separation of the pintle and hook tongues from the side bars.

The successive steps of the operation may be summarized as follows:

65 The bottom of the stock is prick punched

or indented at the future point of separation of pintle tongue and side bars. I illustrate a sharp-pointed punch but obviously a blunt or rounded punch might be used.

70 As the strip moves forward one step, both the top and bottom of the link are scored with an H-shaped score, the transverse arm of the H indicating the separation between the opposed end edges of hook and pintle tongue, the side scores of the H extending along the side bars from end to end of the future inside aperture of the link.

75 At the next forward step a severing knife separates the hook and pintle tongues along the score L⁵ and begins the rolling or curvature of the ends of the two tongues and initiates the separation of the two tongues from the side bars.

80 At the next step, a second knife or punch element further bends the ends of the two tongues and further separates them from the side bars, the end of the hook tongue being bent in an arc substantially concentric with the future arc of the completed hook. At the same step, the opposite ends of the longitudinal scores are indented as at L¹², to 85 prevent further tendency of the metal to tear or fault along the line of score.

90 The next step, the separation of the hook tongue from the side bars, is completed and the entire hook is bent downwardly from the stock, the pintle tongue being also further bent. The line of separation between the two links is also made along the score L¹⁶.

95 Up to this point the sides of the stock 100 have been straight and there has been no distortion of the side bars. At the next step, however, the link is bent, as shown at the left end of Figure 2, and the hook and pintle bars are bent or rolled into the form there shown. The bending of the link has a double function. In the first place the bending throws the end of the hook tongue back and enables its curved end to clear the die when the link is carried upwardly after the forming impact and prior to its next forward movement. The bending has the further function of moving the end of the link down so that it will clear and pass beneath that portion of the punch which depends beneath upon the severed link blank.

110 The link is now ready to be severed from the stock, and after its next forward movement it is sheared off along the score L¹⁶ and 115 is carried downwardly by the punch element N² toward the lower forming die, where the hook and pintle tongues are bent into final form. The hook tongue, since it depends farther from the link than the pintle tongue, 120 is the first to contact the die and is rolled by the semi-cylindrical die surface N¹⁵ into cylindrical form. When the link has been carried so far down that the pintle tongue also 125 contacts the die, it is bent into finished form. 130

Since it is bent or compressed more highly than the larger hook tongue, and since the bend or angle is much more acute, the crease or groove along the inside of its bend is extremely important in preventing weakening and strain of the material and in allowing for space for the compression of the material.

The pintle of the precedingly completed link is positioned within the arc of the hook tongue as it is being curled into final form, and it therefore curls about the pintle and passes through the central aperture of the preceding link. The link thus completed is drawn forwardly away from the stock, and at the next movement of the stock the succeeding link is fed forward for separation and final formation.

Since there are necessarily deep cavities between the individual die elements, and since these cavities tend to become filled with chips and dust, I have provided lateral apertures R in the sides of the die block for the easy removal of such foreign material.

I claim:

1. In a machine for making chain links from a strip of sheet metal stock, comprising an opposed die and punch, each having a plurality of elements positioned therealong, for progressive action upon strip stock passing therebetween, means for guiding said strip between and out of contact with said elements intermediate the forming impacts, comprising pairs of edge engaging strip guide members, one pair mounted upon the punch and one upon the die.

2. In a machine for manufacturing chain from strip stock comprising opposed die and punch elements and means for passing said strip stock therebetween, means for guiding said strip stock forwardly between said elements, and for holding said strip stock out of contact with said elements intermediate the forming impact, comprising two pairs of strip edge engaging guides, one mounted upon the die and one upon the punch, said pairs of guides being longitudinally widely spaced.

3. In a machine for making chain links from a strip of sheet metal stock, comprising an opposed die and punch, each having a plurality of elements positioned therealong for progressive action upon strip stock passing therebetween, means for maintaining said strip between and out of contact with said elements intermediate the forming impacts, comprising in part elements yieldingly mounted on the punch and depending therefrom, and shaped to grasp the opposed edges of the strip, and a yieldingly mounted element upon said die adapted to lift the stock from the die upon the recession of the punch.

4. In a machine for making chain links from a strip of sheet metal stock, comprising an opposed die and punch, each having a plu-

rality of elements positioned therealong for progressive action upon strip stock passing therebetween, means for maintaining said strip between and out of contact with said elements intermediate the forming impacts, comprising in part elements yieldingly mounted on the punch and depending therefrom, and shaped to grasp the opposed edges of the strip, and a yieldingly mounted element upon said die adapted to lift the stock from the die upon the recession of the punch, said elements depending from the punch being adapted to remain in contact with the die until the punch has receded from the die a predetermined distance.

5. In a machine for manufacturing chain from strip stock comprising opposed die and punch elements and means for passing strip stock therebetween, guides for such stock comprising a pair of opposed grooved rollers rotatable about vertical axes adjacent the point of entry of the strip between the dies and punch, and a pair of supporting elements adapted to engage and partially inclose the opposite edges of the strip, said supporting elements being longitudinally widely spaced from said rollers, one pair being mounted on the punch and one on the die.

6. In a machine for making chain from strip stock, comprising an opposed die and punch, each having a plurality of elements positioned therealong for progressive action upon the strip stock passing therebetween, means for clearing said stock from said opposed punch and die elements intermediate the forming excursions of the punch, comprising guide elements depending from the punch and adapted to engage the edges of the stock, and additional stock clearing means comprising stripping plungers mounted along the punch and laterally aligned with the stock engaging members thereof and adapted to engage the outer edges of the stock.

7. In a machine for making, from a continuous strip of sheet metal stock, chain links having pintles and hooks struck from the center of the link, comprising an opposed die and punch, each having a plurality of elements positioned therealong for progressive action upon strip stock passing step by step therebetween, an H-shaped scoring knife adapted to score the blank to outline the inner edges of the side bars from end to end of the inside aperture of the link and to outline the separation between the opposed edges of hook and pintle tongues, and means for indenting the surface of the blank at the ends of the longitudinal arms of the H-shaped score.

8. In a machine for making chain from strip stock comprising an opposed die and punch, each having a plurality of elements positioned therealong for progressive action upon the strip stock passing therebetween,

a pair of rotary guides positioned on the die adjacent the point of entry of the stock between die and punch, said guides being vertically movable, a pair of strip edge engaging members positioned on the punch at a point longitudinally spaced from the rotary guides and adapted to lift the stock from the die after a predetermined upward movement of the punch.

9. In a machine for making chain from strip stock comprising an opposed die and punch, each having a plurality of elements positioned therealong for progressive action upon the strip stock passing therebetween, a pair of rotary guides positioned on the die adjacent the point of entry of the stock between die and punch, said guides being vertically movable, a pair of strip edge engaging members positioned on the punch at a point longitudinally spaced from the rotary guides and adapted to lift the stock from the die after a predetermined upward movement of the punch, said members being vertically movable in relation to the punch, and yielding means, operative upon the recession of the punch from the die, to thrust them downwardly a predetermined distance from the face of the punch.

10. In a machine for making chain from strip stock comprising an opposed die and punch, each having a plurality of elements positioned therealong for progressive action upon the strip stock passing therebetween, a pair of rotary guides positioned on the die adjacent the point of entry of the stock between die and punch, said guides being vertically movable, a pair of strip edge engaging members positioned on the punch at a point longitudinally spaced from the rotary guides and adapted to lift the stock from the die after a predetermined upward movement of the punch, said members being vertically movable in relation to the punch, and yielding means, operative upon the recession of the punch from the die, to thrust them downwardly a predetermined distance from the face of the punch, and additional stock engaging members on the punch adapted to thrust the stock downwardly away from the punch.

11. In a machine for making chain from strip stock comprising an opposed die and punch, each having a plurality of elements positioned therealong for progressive action upon the strip stock passing therebetween, a pair of strip edge engaging guides positioned on the die adjacent the point of entry of the stock between die and punch, a pair of strip edge engaging supports depending from the punch at a point longitudinally spaced from said guides, the die being recessed to receive said supporting members when the punch is in operative contact with the die.

12. In a machine for making chain from strip stock comprising an opposed die and

punch, each having a plurality of elements positioned therealong for progressive action upon the strip stock passing therebetween, a pair of strip edge engaging guides positioned on the die adjacent the point of entry of the stock between die and punch, a pair of strip edge engaging supports depending from the punch at a point longitudinally spaced from said guides, the die being recessed opposite said supports to permit the strip supported thereby to rest upon and be fully contacted by the die during the forming impact of the punch, and means for thrusting said supports downwardly from the punch upon the recession of the punch from the die, and means for limiting their downward movement at a predetermined point.

Signed at Chicago, county of Cook and State of Illinois, this 2nd day of June, 1924.
